(57) **CLAIM**

The ornamental design for a compartmented backpack, as shown and described.

DESCRIPTION

FIG. 1 shows a perspective view of the compartmented backpack.

FIG. 2 shows a front side elevation view of the compartmented backpack.

FIG. 3 shows a rear side elevation view of the compartmented backpack.

FIG. 4 shows a left side elevation view of the compartmented backpack.

FIG. 5 shows a right side elevation view of the compartmented backpack.

FIG. 6 shows a top plan view of the compartmented backpack; and,

FIG. 7 shows a bottom plan view of the compartmented backpack.

The shade lines in the Figures show contour and not surface ornamentation.

1 Claim, 5 Drawing Sheets
